UNITED STATES PATENT OFFICE.

JOHN J. SCHMIDT AND ALBERT L. BRICE, OF FREDERICK, MARYLAND, ASSIGNEES TO THE FREDERICK IRON & STEEL COMPANY, OF FREDERICK, MARYLAND, A CORPORATION OF MARYLAND.

CENTRIFUGAL PUMP.

Application filed October 31, 1924. Serial No. 747,071.

To all whom it may concern:

Be it known that we, JOHN J. SCHMIDT and ALBERT L. BRICE, citizens of the United States, residing at Frederick, in the county of Frederick and State of Maryland, have invented certain new and useful Improvements in Centrifugal Pumps, of which the following is a specification.

Our invention relates broadly to centrifugal pumps and more particularly to a system for insuring a tight seal between high and low pressure areas in the pump system, for increasing the efficiency thereof.

One of the objects of our invention is to provide a removable and adjustable sealing or wearing ring structure for the impeller of a centrifugal pump whereby the impeller may be at all times properly located in relation to the ring structure by adjustment of the sealing or wearing ring structure.

Another object of our invention is to provide a pair of sealing and wearing rings on opposite sides of an impeller in a rotary pump structure for compensating for and minimizing slip past the rings of the impeller within the pump structure.

Still another object of our invention is to provide a structure of adjustable sealing and wearing ring for centrifugal pump having a wearing face adapted to register with a corresponding cooperating annular face or faces on an impeller with means for adjusting the sealing or wearing ring to any desired position.

A further object of our invention is to provide a pair of sealing and wearing rings on opposite sides of an impeller in a centrifugal pump where the impeller is provided with annular faces having spiral grooves therein directed toward the axis of the pump in the direction of rotation thereof forming a seal between the impeller and the sealing and wearing ring structure and preventing undesired leakage from high pressure areas to low pressure areas and thereby increasing the efficiency of the pump system.

Our invention will be more clearly understood from the specification hereinafter following by reference to the accompanying drawings, in which:

Figure 1 is a partial cross-sectional view through the pump structure showing the ap-

plication of the sealing or wearing rings of my invention;

Fig. 2 is an enlarged partial cross-sectional view showing a slightly modified construction of sealing or wearing ring and its arrangement with respect to the impeller of a centrifugal pump; and

Fig. 3 is a side view of the impeller showing the sealing means which we provide in one of the flat annular faces of the impeller.

Referring more particularly to the drawings, the pump is shown mounted upon base 1 having a pump casing 2. The central outlet for the pump is represented at 3. The inlet ports are represented at 4 and 5 delivering fluid to opposite sides of the impeller 12. The impeller is carried by a shaft 8 which passes through packing boxes 6 and 7 and is journaled in bearings 9 and 10. Power is delivered by rotary shaft 8 through coupling 11 for any desired purpose. In each side of the pump casing 2, we provide annular ring members 14 and 15 on opposite sides of the impeller 12. Each ring member is internally screw-threaded to receive sealing and wearing rings 18 and 19. The sealing and wearing rings 18 and 19 may be adjusted axially toward or away from faces 16 and 17 of the impeller 12. The screw-threads in one of the ring members are formed opposite to the screw-threads in the other ring member, enabling the sealing and wearing rings 18 and 19 to be readily adjusted into position where they register with the annular faces 16 and 17 of the impeller 12. The opposed relation of the screw threads in the ring members eliminates the possibility of the sealing or wearing rings binding against the faces of the impeller during operation in the event that the wearing and sealing rings become loose in the ring members. That is to say, the sealing rings are screw threaded into the ring members in such direction that the rotation of the impeller is in such relative direction with respect to the screw threading of the wearing rings that the wearing rings tend to tighten in the ring members rather than loosen. The arrangement is particularly effective in increasing the life of the pump and offers substantial protection to the impeller. Ring member 14 is pro-

vided with an annular wall 24 and a flange

2
face 22 in which the set screws 20 are positioned, enabling the sealing and wearing ring 18 to be held in position when it has been finally located in a desired position 5 with respect to face 16 of the impeller 12. The ring member 15 is provided with an annular wall 25 and a face 23 in which the set screws 21 are positioned, enabling the sealing or wearing ring 19 to be held in position 10 when it has been located in a selected position with respect to the face 17 of the impeller 12. The arrangement of parts is more clearly illustrated in Fig. 2. The sealing or wearing ring 18 may be provided with 15 a pocket or plurality of notches 29 to facilitate the adjustment of the sealing and wearing ring in position by means of a spanner wrench when the set screws 20 are loosened and when it is desired to change the position 20 of the sealing and wearing ring with respect to the annular face 16 of the impeller 12. After the desired adjustment is made to secure the proper clearance between the annular face of the sealing and wearing 25 ring 18 and the annular face 16 of impeller 12, the set screws 20 are tightened, securing the sealing and wearing ring in a permanent position. The sealing and wearing ring 18 may be provided with an extended 30 lip 26, which extends under the annular wall of the impeller 12 to insure a seal between the high and low pressure areas in the pump. In order to further insure against 35 the leakage of water past the sealing and wearing rings we provide a spiral groove 27 in each of the annular faces 16 and 17 of the impeller 12. The spiral groove 27 is directed in the same direction as that in which the vanes 28 of the impeller 12 are directed and is directed toward the axis of the 40 pump in the direction of rotation thereof.

In this way any leakage which might normally tend to occur is forced back into the high pressure area 3 thus reducing the short 45 circuit leakage and consequently increasing the efficiency of the pump.

It will be understood that the sealing and wearing ring 18 may be constructed in a variety of forms and that the face thereof 50 may have any desired formation with which to cooperate with a corresponding face on the impeller. The sealing and wearing ring may be removed from time to time as it becomes worn. It will be also understood that 55 various means for securing the sealing and wearing ring in position may be provided and that the arrangement shown in the drawings is given merely for illustrative purposes. The clearance between the impeller faces and the wearing ring faces is 60 substantially vertical enabling an easy adjustment of the sealing and wearing rings. The entire rotor can be shifted by adjustment of sealing and wearing rings 18 and 65 19. The clearances between wearing faces

16 and 17 on opposite sides of impeller 12 and sealing and wearing rings 18 and 19 are not necessarily equal. The sealing rings are each independently adjustable, that is to say, the screws 20 may be loosened and the 70 rings advanced or retracted in the screw threaded ring members 14 and 15 by use of a spanner wrench fitting into the notches represented at 29. The fact that the sealing and wearing rings are readily removable gives increased life to the pump at the same time maintaining the original clearances and efficiency of the pump by slight adjustment of the sealing and wearing rings 75 from time to time to take up the wear. 80

As we have previously pointed out the arrangement of the sealing and wearing rings in combination with the impeller and the pump casing serves to minimize slip past the rings and the impeller within the pump structure, that is to say, the pressure developed is effectively utilized as head with minimum losses. 85

While we have described our invention in certain particular embodiments, we desire 90 it understood that modifications may be made and that no limitations upon the invention are intended other than are imposed by the scope of the appended claims.

What we claim and desire to secure by 95 Letters Patent of the United States is as follows:

1. A centrifugal pump comprising in combination a casing, a shaft journaled in said casing, an impeller carried on said shaft, flat annular faces on each side of said impeller, a pair of circular members carried by said casing on opposite sides of said impeller, opposite screw threads in said members, and a pair of removable sealing and wearing 100 rings engaged by said screw threads and having flat annular faces corresponding to said flat annular faces on each side of said impeller and aligned therewith. 105

2. A centrifugal pump comprising in combination a casing, a shaft journaled in said casing, an impeller carried on said shaft, flat annular faces on each side of said impeller, a pair of circular members carried by said casing on opposite sides of said impeller, screw threads in said members, a pair 110 of removable sealing and wearing rings carried by said screw threads and means for securing said sealing and wearing rings in position relative to said members, said rings having flat annular faces corresponding to said flat annular faces on each side of said impeller and aligned substantially therewith. 115

3. A centrifugal pump comprising in combination a casing, a shaft journaled in said casing, an impeller carried on said shaft, a pair of annular faces on each side of said impeller, a pair of circular members carried by said casing on opposite sides of said 120 125 130

impeller, screw threads on said members, and a pair of removable sealing and wearing rings carried by said screw threads, said sealing and wearing rings having annular faces registering with the annular faces on each side of said impeller.

4. A centrifugal pump comprising in combination a casing, a shaft journaled in said casing, an impeller carried on said shaft, a pair of annular faces on each side of said impeller, a pair of circular members carried by said casing on opposite sides of said impeller, screw threads on said members, a pair of removable sealing and wearing rings carried by said screw threads having faces registering with the faces on said impeller and a spiral groove in each of the faces of said impeller.

5. A centrifugal pump comprising in combination a casing, a shaft journaled in said casing, an impeller carried on said shaft, a pair of annular faces on each side of said impeller, a pair of circular members carried by said casing on opposite sides of said impeller, screw threads on said members, a pair of removable sealing and wearing rings carried by said screw threads having faces registering with the faces on said impeller and means on said impeller faces for sealing the gap between said sealing and wearing rings and said faces on said impeller.

6. A centrifugal pump comprising in combination a casing, a shaft journaled in said casing, an impeller carried on said shaft, a pair of annular faces on each side of said impeller, a pair of circular members carried by said casing on opposite sides of said impeller, screw threads on said members, a pair of removable wearing rings carried by said screw threads having faces registering with the faces on said impeller and a spiral groove formed in each of said impeller faces and extending toward the axis of said impeller in the direction of rotation thereof for sealing the gap between said wearing rings and said faces on said impeller.

7. A centrifugal pump of the double suc-

tion type comprising in combination a casing, a shaft journaled in said casing, an impeller carried by said shaft, said impeller having a pair of annular faces thereon, a ring member carried in each side of said casing, a wearing ring carried in each of said members, each of said wearing rings having an annular wearing face, and means for axially adjusting each of said wearing rings independently within said ring members.

8. A centrifugal pump comprising in combination a casing, a shaft journaled in said casing, an impeller carried by said shaft, said impeller having annular faces at each side thereof, a sealing and wearing ring located in each side of said casing adjacent the annular faces on said impeller, and means for independently adjusting the relative distances between said sealing and wearing rings and said annular faces on said impeller.

9. A centrifugal pump comprising in combination a casing, a rotatable shaft extending into said casing, an impeller carried by said shaft, an annular face on said impeller, a ring member carried in said casing and a removable wearing and sealing ring positioned in said ring member having a face corresponding to the annular face on said impeller, and means for axially adjusting said wearing and sealing ring with respect to the annular face on said impeller.

10. A centrifugal pump comprising in combination a casing, a rotatable shaft extending into said casing, an impeller carried by said shaft, a ring member carried in said casing adjacent said impeller, a sealing and wearing ring positioned in said ring member, and cooperating faces of any contour on said impeller and said sealing and wearing ring, said faces being axially adjustable with respect to each other for minimizing slip past said impeller.

In testimony whereof we affix our signatures.

JOHN J. SCHMIDT.
ALBERT L. BRICE.
